CLAIM

The ornamental design for an earphone, as shown and described.

DESCRIPTION

FIG. 1 shows a top plan view of an earphone showing my new design;

FIG. 2 shows a front perspective view thereof;

FIG. 3 shows a front elevation view thereof;

FIG. 4 shows a side elevation view thereof;

FIG. 5 shows a rear elevation view thereof; and,

FIG. 6 shows a bottom plan view thereof.

In the drawings, the broken lines depict portions of the earphone that form no part of the claimed design.
